United States Patent Office

Des. 227,513

Patented June 26, 1973

227,513

BABY BOTTLE HOLDER

Roland Edward Lievendag, 100 SW. 12th Ave.,
Boca Raton, Fla. 33432

Filed Aug. 9, 1971, Ser. No. 170,424

Term of patent 14 years

Int. Cl. D24—04

U.S. Cl. D83—8 R

Fig. 2.

Fig. 1.

Fig. 3.

FIG. 1 is an elevational view of a baby bottle holder showing my new design;

FIG. 2 is a top plan view thereof;

FIG. 3 is a sectional view thereof taken on line 3—3 of FIG. 2.

I claim:

The ornamental design for a baby bottle holder, as shown.
